UNITED STATES PATENT OFFICE.

JOHN TAYLOR, OF TROY, NEW YORK.

RAILWAY-CAR TRUCK.

SPECIFICATION forming part of Letters Patent No. 598,449, dated February 1, 1898.

Application filed July 23, 1897. Serial No. 645,723. (No model.)

To all whom it may concern:

Be it known that I, JOHN TAYLOR, of Troy, in the county of Rensselaer and State of New York, have invented certain new and useful Improvements in Trucks; and I hereby declare that the following is a full, clear, and exact description thereof, reference being had to the accompanying drawings, which form part of this specification.

10 This invention is an improvement in trucks for electric railways; and it has especial reference to the connections between the truck-frame and suspending springs and to certain other novel and useful details of construction and combinations of parts hereinafter described and claimed.

In the drawings, Figure 1 is a side elevation of a complete truck embodying my improvements. Fig. 2 is an enlarged vertical longitudinal section through one of the pedestals and connected part of frame, spring, and spring-hangers. Fig. 3 is a detail transverse section on line 3 3, Fig. 2, looking toward the pedestal. Fig. 4 is a view of the hanger-casting detached. Fig. 5 is a view of a slight modification of this casting. Fig. 6 is a vertical section on line 6 6, Fig. 1, showing the center stay. Fig. 7 is a transverse section of the stay on line 7 7, Fig. 6. Figs. 30 8, 9, and 10 are detail views illustrating the connection of the motor-sustaining bar to the frame.

Referring to the drawings, A A designate the pedestals, which are connected at top by parallel side bars B B, that are bolted to flanges a of the pedestals, leaving a clear space therebetween for the accommodation of the inverted semi-elliptic springs C, which rest upon the axle-boxes D, while their outer ends are connected by links E to hanger-castings F, underlying the side bars B B, as shown. Each casting F is provided with side lips $f f'$ to embrace the outer edges of the opposite bars B and prevent it twisting or turning thereunder, and the inner lip f' of the casting projects upward sufficiently to carry an inwardly-projecting teat f^2 , Fig. 4, which is adapted to engage a recess or hole a in the inner side bar, so as to uphold the casting and prevent longitudinal slip thereof on bars B. Instead of a teat f^2 the lip may be secured in

place by a countersunk or flush-sunk bolt f^4 , passing through a hole f^2 in lip f' , the teat being omitted. I prefer the teat, however, as the nut on the bolt is apt to work off or be sheared off and is more troublesome than the teat. Each casting is also provided with pairs of depending ears F', which are perforated for the passage of a transverse bolt G, which can be retained by a cotter g. The casting is, moreover, slotted, as at F³, between the ears for the accommodation of the lower ends of the pair of links E, which are hinged on bolt G, and their upper ends are loosely connected by a suitable bolt or rivet to the eye 65 on the adjoining end of the spring C, as shown. Preferably the links E are connected to the spring by stout countersunk rivets, so that the spring and links can play vertically freely, but snugly, between the side bars B B. 70 It will be observed that the outermost ears F' are directly under bars B B, so that the principal lift or weight of the load is sustained by the castings at points directly under the side bars B B, the two inside ears serving 75 principally as guides or loops to prevent bolt G bending. It will be observed that the half-elliptic spring with the links about fills the space between the side bars B B and are kept from lateral vibration thereby, while free to 80 expand and react according to the strains incident to usage. This construction has been tested and highly approved, because of its simplicity, ease of access, and interchangeability.

The lower ends of the legs of each pedestal A are connected by a bottom stay H, the ends of which fit into rabbets A' in the legs and are retained by bolts h, dropped through vertical openings in the bottom webs of the legs, 90 as shown. In the truck shown the weight of the car is carried at its extreme ends, and consequently the braces and trusses tend to close the jaws of the pedestals upon each other and cramp the axle-boxes. This is overcome by 95 the bottom stays H, arranged as shown and described. The inner leg of each pedestal is, moreover, provided with a lateral socket A² for the reception of the end of a flat bottom bar J, which is set vertically edgewise, and 100 an important feature is the fact that the socket A² is so located that the bolt h can be dropped

in behind the socket and end of bar A, so that it can be removed and replaced without disturbing bar A.

The bottom bar J and upper bars B B are rigidly connected by a center stay K, Fig. 7, the upper end of which is embraced between bars B B and lipped thereover and thereunder, as shown at $k^2 k^3$, and its lower end is also lipped over and under bottom bar J, as shown at $k^2 k^3$, so that shearing of the securing-bolts K' K' is absolutely prevented.

The motor-hanging bars L are preferably connected to the bars J by means of angle-bolts M, and the ends of bars L are reduced, as at L', and forged with eyes L² for the passage of bolts M. The motors can be easily raised or lowered slightly in relation to the frame by simply turning bars L up or down, as shown in Figs. 8 and 10, respectively.

20 The other parts of the truck can be constructed as in some of my former patents—No. 437,167, for instance—or in any desired manner.

It will be observed that the entire weight of the car-body is placed at the extreme ends of the truck, and consequently the weight of the car-body tends to force the pedestals toward each other and compress bars J longitudinally. The ends of said bars J are made square and accurately fitted into sockets A² of the pedestals and are held therein by the compression due to the weight of the car-body, no bolts or other fastenings being required, because the pedestals tend to close upon the bars, which become really thrust-bars and prevent closing up of the pedestals.

Having thus described my invention, what I therefore claim as new, and desire to secure by Letters Patent thereon, is—

40 1. The combination of the side bars B, B, of a truck-frame, and the hanger-casting attached thereto and thereunder at opposite

sides of the pedestal, having pairs of ears; and the links hinged to said castings by a bolt transfixing said ears; with the spring having eyes on its ends hinged to the upper ends of said links, for the purpose and substantially as described.

2. The combination with the castings F having ears F' and lips f, f', substantially as described; of the links E connected to said castings, and the spring connected to said links, for the purpose and substantially as described.

3. The combination with the side bars of the truck-frame, the inverted semi-elliptic spring located intermediate said bars, and the depending links swung from the ends of said spring; of the lipped castings F underlying said bars and provided with slots F³ and ears F', and the bolt G transfixing said links and ears, for the purpose and substantially as described.

4. The combination of the parallel side bars B, B, and the hanger-castings F thereunder each provided with upstanding flange f', having a teat f², engaging an opening in one of the bars to retain the casting in place; with the spring, and the links connecting said spring to said castings for the purpose and substantially as described.

5. The combination with the side bottom bars of a truck, of motor-sustaining bars L having reduced ends L'; and the angle-bolts M for securing said sustaining-bars to the bottom bars of the truck, for the purpose and substantially as described.

In testimony that I claim the foregoing as my own I affix my signature in presence of two witnesses.

JOHN TAYLOR.

In presence of—
PAUL COOK,
FRANK SHRAUDER.
